UNITED STATES PATENT OFFICE.

GEORGE EUGENE MITTINGER, OF YOUNGSTOWN, OHIO.

METALLIC KEG.

Application filed April 22, 1922. Serial No. 555,989.

To all whom it may concern:

Be it known that I, GEORGE E. MITTINGER, a citizen of the United States, residing at Youngstown, in the county of Mahoning and 5 State of Ohio, have invented certain new and useful Improvements in Metallic Kegs, of which the following is a specification, reference being had therein to the accompanying drawing.

10 This invention relates to improvements in metallic kegs, and the object is to provide a metallic container for transporting bolts, rivets and nails, to take the place of the ordinary wooden keg that is used for that purpose.

One object of the invention is to make a metallic keg composed of a plurality of interlocking staves, preferably, four in number, whereby they may be shipped in nestled 20 relation and quickly assembled by the user.

A further object of my present invention is to construct a metallic keg, composed of a plurality of staves which have on their edges longitudinally extending interlocking 25 grooves, whereby the grooves may be slid together by a longitudinal movement, and each stave provided with longitudinally extending lugs adapted to pass through openings in the head and then bent over.

30 A further object of my present invention is to provide a metallic keg composed of a plurality of staves, the staves provided with longitudinally extending box-shaped grooves on opposite edges, the bead on one edge of 35 the stave being at the inner side, and the bead at the other edge being on the outer side, whereby the staves may be locked together by a longitudinal movement, each stave having members projecting beyond its 40 edge and adapted to pass through the head of the keg and turned over to fasten it in position.

Still another object of the invention is to 45 provide a metallic keg composed of a plurality of staves, each stave having one edge bent inwardly and backwardly upon the stave, and the other edge of the stave bent outwardly and backwardly forming box-like beads at opposite sides of the stave, 50 whereby they may be locked together by a longitudinal movement, the edge of the stave provided with projected members to pass through the openings and turned down for securing the head to the stave.

Another object of my invention is to provide a metallic keg composed of a plurality of longitudinally extending staves, the edges of the stave doubled back upon itself and then each edge bent into a box-shaped bead, the edge of the stave provided with projected members adapted to pass through the head and turned over for securing it and the head together. 55

A further object of my present invention is to provide a keg composed of a plurality of staves, both edges of the stave doubled outwardly and backwardly upon itself, one edge of the stave formed into an outwardly turned box-like bead, and the opposite edge with an inwardly and backwardly turned 60 box-shaped bead, whereby they will interlock, the edge of the stave provided with longitudinally extending members adapted to pass through openings in the head of the keg and turned over. 65

Another object of my present invention is to provide a keg composed of a plurality of staves, the opposite edges of the stave having box-shaped beads in the opposite side of the stave, the box-shaped bead projecting 70 beyond the edge of the stave to form fastening members through the head of the keg. 75

Another object of my invention is to provide a keg composed of a plurality of staves, each stave having at opposite edges box-shaped beads and intermediate its ends a longitudinally extending doubled portion, the beads and the doubled portion extending beyond the edge of the stave to pass 80 through the openings in the head of the keg 85 and turned over thereon to fasten the parts together. 90

In the accompanying drawings:—

Figure 1 is a side elevation of my improved keg. 95

Fig. 2 is an end plan view of the keg.

Fig. 3 is a cross-section on the line 3—3 of Fig. 2.

Fig. 4 is a cross-sectional view of my improved keg. 100

Fig. 5 is a sectional view showing the way of nesting the heads in position for shipping purposes.

Fig. 6 is a detached perspective view of one of the staves, with a portion of the adjoining stave in position to interlock therewith. 105

Fig. 7 is a sectional view, showing the

staves nested together for shipping purposes.

Fig. 8 is an enlarged exaggerated view of the interlocking beads.

Fig. 9 is an edge view of one of the staves 5 before it is curved.

Heretofore, wood kegs have been provided for shipping nuts, rivets, nails, etc., but they have been found to burst open if they are dropped from a distance, or roughly 10 handled. By means of a keg, such as I here disclose, I have provided a structure which it is impossible to break under ordinary rough usage and will stand being thrown from or dropped from a consider- 15 able height without tearing apart.

Referring now to the drawings, my improved keg consists of a plurality of staves 1, as here shown, preferably four in number. These staves are given the proper 20 curve for the keg that is to be made. In making the staves of my improved keg, the opposite edges of the stave are doubled back upon itself, as shown at 2, and intermediate its width it is formed with a doubled back 25 bend 3. Each edge of each stave is provided with a longitudinally extending box-shaped bead, the bead 4 being formed in the doubled portion 2, whereby it is of a doubled thickness, thus giving increased 30 strength. It will be observed that the box-shaped bead 4, is formed on the inside of the stave 1, thus forming an opening 5 at its outer side. The opposite edge of the stave is provided with a box-shaped bead 6, 35 formed in the doubled portion 2, and this bead is bent so that it is on the outside of of the stave forming an opening 7 at the inner side of the stave. Each stave is formed alike, whereby one stave can be in- 40 terlocked with the other stave by a longitudinal movement.

When the staves are locked by the longitudinal movement, they assume the position shown in Fig. 8. It will be understood that 45 the beads do not tightly fit and that the staves may be moved to some extent back and forth.

By reference to Fig. 6, it will be seen that the beads project beyond the edges of the 50 staves, thus forming projecting members, and that the bead portion 3, intermediate the stave, also projects beyond its edge. These projections form members by means 55 of which the stave is attached to the heads of the keg. It will be observed by reference to Fig. 8, that in the form here shown, when the staves are assembled, there will be eight thicknesses of the metal at the joint. This makes a very rigid edge for 60 each stave and makes a very rigid keg when it is assembled.

When the keg is assembled, the ends of the extending beads pass through suitable openings 8 formed in the head 9 of the keg.

65 The ends project considerably beyond the

head 9 and are doubled inwardly, as shown at 10, which securely fastens the head and the stave together. The head 9 is provided with a U-shaped bend 11, whereby its outer edge is doubled, as shown at 12, and the top 70 of the doubled portion is provided with the openings 8, through which the projecting members extend and are doubled inward. The head also is provided with an upwardly extending portion 13, whereby the U-shaped bend 11 forms a place for the fingers 75 in grasping the keg and handling it, or, in other words, a chime. For the purpose of strengthening the head 9 it is provided with a plurality of radially downwardly pressed 80 grooves 14, which extend from the outer edge inwardly to an upwardly extending bent portion 15, which forms a place 16 adapted to receive a pasted label giving the contents of the keg, its weight, etc. 85

By reason of the doubled edges of the staves, which are formed into box-shaped beads or grooves, when the keg is assembled and the extended ends driven down into the bent shape shown, a secure fastening of the 90 head is obtained and it cannot be torn away. While I prefer to make the box-shaped grooves double, as shown, because of the increased strength, yet it might be made single, which would give a four-ply joint. 95

In Fig. 7, the manner of nesting the staves for shipping purposes is shown, from which it will be seen that they will nest very closely.

A keg constructed as here shown and described is very strong and rigid and stands almost any degree of punishment without breaking apart.

It will be understood that the keg is not intended to be used again, since it can be 105 made very cheaply, for only a few cents. Thus when the keg is received by the user, the bent over ends are cut off with a chisel, or removed in any other way, since the keg is not to be used again. 110

I desire it to be understood that variations may be made in the specific construction here shown without departing from the spirit and scope of my invention.

Having thus described my invention, 115 what I claim and desire to secure by Letters Patent is:—

1. An improved metallic keg, consisting of a plurality of longitudinally extending staves, each stave having at its opposite edges interlocking beads which project beyond the edge of the stave, and a head having openings to receive the projections which are bent downwardly, for the purpose described. 120

2. An improved metallic keg, comprising a plurality of longitudinally extending staves, each stave having longitudinally extending interlocking beads projecting beyond the end of the stave, a top having 130

- openings for the projections, the projections bent inwardly and downwardly.
3. A keg of the type described, comprising a plurality of staves having at each edge 5 a box-like longitudinal interlocking bead projecting beyond the edge of the stave, a head having openings through which the beads project, the beads bent downwardly around the head.
- 10 4. An improved metallic keg, consisting of a plurality of staves having at each edge a longitudinally interlocking bead projecting beyond the ends of the stave, a top having at the edge a U-shaped portion, and the 15 projections doubled inwardly and downwardly into the U-shaped portion.
5. An improved metallic keg, comprising a plurality of longitudinally extending staves, each stave having at one edge an inwardly extending box-shaped groove and at the other edge an outwardly extending box-shaped bead, the staves interlocked and the bead projecting beyond the end of the stave, a head having openings for the projecting 25 beads, and the beads turned down, for the purpose described.
6. An improved metallic keg, comprising a plurality of staves, each edge of the stave provided with a doubled portion bent into 30 box-like longitudinally extending beads, the ends of the beads projecting beyond the end of the stave, the head having peripheral openings through which the beads pass, and the beads turned downwardly for the purpose described.
- 35 7. An improved metallic keg, comprising a plurality of longitudinal staves, having at opposite edges box-like longitudinally extending beads, and a longitudinally extending doubled bead between its ends, the beads projecting beyond the end of the stave, and a head having peripheral openings through which the beads extend, the beads doubled downward, for the purpose described.
- 40 8. An improved metallic keg, comprising a plurality of staves having at opposite edges interlocking beads which project beyond the end of the stave, a head provided with a doubled periphery, the doubled portion having vertical openings through which 45
- the ends of the beads project and are doubled down, for the purpose described.
9. An improved metallic keg, comprising a plurality of staves having at the opposite edges interlocking beads projecting beyond 55 the end of the stave, a head having a U-shaped and a doubled portion at its periphery, the doubled portion having vertical openings through which the ends of the beads pass and are doubled down, for the 60 purpose described.
10. An improved metallic keg, comprising a plurality of longitudinally extending staves having at opposite edges interlocking longitudinally extending beads, the beads 65 extending beyond the ends of the staves, of a head having a doubled portion and a U-shaped bend, the doubled portion having vertical openings through which the beads extend and are doubled downward, the head 70 having radiating grooves which extend from the U-shaped portion to a central bead, for the purpose described.
11. As a new article of manufacture, a stave for metallic kegs, consisting of a 75 curved sheet having at its opposite edges longitudinally extending box-like beads extending beyond the end of the stave for the purpose described, the box-like beads consisting of a double thickness of metal. 80
12. As an improved article of manufacture, a stave consisting of a curved sheet having at one edge an outwardly extending box-shaped longitudinal bead, and at its opposite edge an inwardly open longitudinal 85 box-shaped bead, the center of the stave having a longitudinally doubled bead, all of the beads extending beyond the end of the stave, for the purpose described.
13. An improved metallic keg, consisting 90 of a plurality of longitudinally extending staves, each stave having at its opposite edges interlocking beads which project beyond the edge of the stave, and a head, the projecting beads bent downward upon the 95 head, for the purpose described.

In testimony whereof I hereunto affix my signature.

GEORGE EUGENE MITTINGER.
